Primary Examiner — Richard Edgar*Assistant Examiner* — Nader Abadir(74) *Attorney, Agent, or Firm* — Ricky Lam(57) **CLAIM**

The ornamental design for a lunch box as shown and described.

DESCRIPTION

FIG. 1 is a front, top, and left perspective view of a lunch box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is a front, top, and left perspective view of the open state of lunch box; and,

FIG. 10 is a front, top, and right perspective view of the open state of lunch box.

The broken lines shown in the drawings represent portions of the lunch box that form no part of the claimed design.
